United States Patent Office

Des. 197,187
Patented Dec. 24, 1963

197,187

COMBINED ILLUMINABLE FIXTURE AND GUARD THEREFOR

Martin Lasker, Flushing, N.Y., assignor to McPhilben
Manufacturing Co., Inc., Brooklyn, N.Y., a corporation
of New York

Filed Dec. 26, 1961, Ser. No. 68,048

Term of patent 14 years

(Cl. D48—23)

FIG. 2.

FIG. 3.

FIG. 1 is a bottom perspective view of a combined illuminable fixture and guard therefor, showing my new design;

FIG. 2 is a side elevation thereof; and

FIG. 3 is a bottom plan view thereof.

The top is open and substantially plain.

What I claim is:

The ornamental design for a combined illuminable fixture and guard therefor, as shown and described.
